UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

OUTDOOR ELECTRIC-LIGHTING FIXTURE.

1,036,064.

Specification of Letters Patent. Patented Aug. 20, 1912.

Application filed July 26, 1909. Serial No. 509,529.

To all whom it may concern:

Be it known that I, REUBEN B. BENJAMIN, a citizen of the United States, residing at Chicago, in the county of Cook and State of Illinois, have invented new and useful Improvements in Outdoor Electric-Lighting Fixtures, of which the following is a full, clear, concise, and exact description, reference being had to the accompanying drawing, forming a part of this specification.

This invention relates to improvements in electric lighting fixtures especially adapted for outdoor use or for use in positions where the device is exposed to the weather.

The object of the invention is to provide a device which is of pleasing appearance, which affords protection for the lamps and which is so constructed that the lamps are made readily accessible for cleaning, replacement and the like.

In the accompanying drawings, Figure 1 is a vertical longitudinal sectional view of a device employing the features of my invention and adapted for the reception of four incandescent lamps; Fig. 2 is a plan view of a member which is employed to hold the protecting globe in position; and Fig. 3 is a bottom plan view of the same, showing also a portion of the bottom of the globe.

In the several figures of the drawings, 5 is a pipe, the upper end of which is screw threaded and screws into a metallic member 6 which is carried by an insulating block 7 secured to the upper side of a metallic cross arm 8. This cross arm carries at its ends insulators 9 to which may be brought a pair of feed wires. The feed wires will lead from the insulators 9 to the insulating block 7 and will pass up through openings 10 in the insulating block to binding screws 11. From these binding screws a pair of wires will lead down through the pipe 5 to the binding terminals of the lamp-receiving sockets as hereinafter explained. The lower end of the pipe 5 screws into a threaded opening in a tripod or crowfoot 12, the feet of which are secured to the upper side of a plate 13. The plate 13 is formed with openings therethrough corresponding in number to the number of lamps which the device is designed to carry. Each of these openings is of suitable size and shape to receive the reduced front end 14 of a lamp socket such as is ordinarily employed on elec-

tric signs. These sockets 15 are secured to the upper side of the plate 13 with the portion 14 of each socket extending downward through the plate, the sockets being held in place by means of screws 16. Each socket 60 is provided with suitable binding screws or the like and the wires which extend down through the pipe 5 will subdivide and extend to the binding screws of the several sockets in a well understood manner, which 65 need not be illustrated. On the under side of the plate 13 is secured a second crowfoot 17, the feet of this tripod being secured to the plate 13 by the same rivets or screws which hold the plate 13 to the feet of the 70 upper tripod. A pipe 18 has its upper end screwed into the tripod member 17 and is provided upon its lower end with means for supporting in position the globe 19 which protects the lamps 20 when the same are inserted into the sockets of the device. A reflector 21 is supported in position over the lamps by means of a collar 22 which surrounds the pipe 18 and is held in position by a set screw 23 which clamps the collar to the 80 pipe. The reflector 21 is formed with a central aperture through which the pipe 18 extends, and is also formed with openings to receive the bases 24 of the lamps.

The lamps that will ordinarily be used in 85 this device are tungsten or other metal-filament lamps having bases of larger diameter than the threaded plug portion which screws into the socket. It will be observed that the enlarged base 24 of each lamp is 90 nearly all concealed when the lamp is in position, the glass body of the lamp extending almost to the surface of the reflector 21, and that the lamp, when it is to be inserted into the socket, must first be passed up through 95 the opening in the reflector. This arrangement affords a device of pleasing appearance, and moreover, the efficiency of the reflector and the lamps in light-giving and reflecting power is greater than with other arrangements in which the lamp is at a considerable distance below the reflector.

Extending over the sockets and the reflector 21 is a combined hood and reflector 25 which is substantially bell-shaped and 105 which extends for a considerable distance beyond the globe 19 on every side. This hood is drawn in at its upper portion to a diameter which is just great enough to accommodate the sockets 15, whereby a pleas- 110

ing appearance is given to this part of the fixture. To further enhance the appearance of the device, a secondary hood or cap 26 is disposed upon the top of the hood 25 and extends up to the cross bar 8. The cap 26 has its lower end flanged inwardly at 27 and the hood 25 has a raised portion 28 which extends up into the cap for a short distance to hold the same in alinement.

Extending around the outer edge of the inner reflector 21 is a ring 29 provided with perforations 30, these perforations being intended to afford ventilation for the space within the globe 19, which space becomes heated when the lamps are in operation. The globe is so supported in position that it may be lowered when it is desired to gain access to the lamps for the purpose of replacing or cleaning same. The means for accomplishing this are such that the globe is supported in its lowered position while the lamps are being cleaned or replaced, and when it is desired to restore the globe to its normal position this may be easily done by lifting the globe until its upper edge passes into the ring 29, whereupon by manipulating a suitable locking device the globe is held in its raised position. For this purpose I provide an extension rod 30 which is arranged to slide up and down in the pipe 18, this rod having a head 31 upon its upper end which fits the inside of the pipe 18, the lower end of the rod being screw threaded at 32. A slide bearing for the rod is provided near the lower end of the pipe 18, this bearing consisting of a ring 33 held in place by rivets 34 which extend through the wall of the pipe. The globe 19 has a central opening in its under side through which extends the pipe 18. A ring-like member 35 extends around the edge of the opening in the globe and has an externally threaded neck 36 which extends up through the opening. Screwed upon this threaded neck is a clamping ring 37. The lower end of the pipe 18 is externally screw threaded, a nut 38 being arranged to screw upon this end of the pipe. The passage through this nut is enlarged at its upper end and receives a downwardly extending neck 39 which is provided on the member 35, so that when the nut 38 is screwed up into position on the lower end of the pipe the member 35, and the globe to which this member is secured, are sustained by the lower end of the pipe. The opening in the nut 38 is made smaller at its lower end and is threaded to receive the threaded end 32 of the rod 30. A pair of set nuts 40 and 41 lock the nut 38 firmly in position on the rod 30. The member 35 is provided with suitable passages 42 for the admission of air into the lower part of the space inclosed by the globe 19. These holes, in combination with the holes 30 in the ring 29, at the upper part of the globe,

are provided to afford suitable ventilation for the space occupied by the lamps.

When the globe is to be lowered, the unscrewing of the nut 38 frees the same from the threaded lower end of the pipe 18 and permits the rod 30 to slide down through the pipe 18 until the head 31 of the rod rests upon the ring 33. The globe is now suspended in position at such a distance below the lamps as to permit the same to be readily reached. When the globe is to be removed altogether this may be easily accomplished by first unscrewing the nut 40 from the lower end of the rod 32 and removing the same. If the member 38 be now unscrewed from the lower end of the pipe 18 the globe, together with the clamping members 35 and 37, may be slipped off the end of the rod 30. If a new globe is to be substituted for an old one the clamping members 35 and 37 may be easily removed from the old globe by unscrewing the member 37 from the threaded neck of the member 35.

Having thus described my invention, what I claim as new and desire to secure by Letters Patent, is:

1. The combination with a plurality of lamp-receiving sockets, and means for supporting said sockets, of means for removably supporting a globe surrounding said sockets, said globe-supporting means including a pipe extending vertically downward from said socket-supporting means, a member adapted to be removably secured to said pipe and to engage the globe to support the same around said sockets, a rod vertically guided within said pipe and secured to said member, and means for limiting the downward movement of said rod.

2. The combination with a plurality of lamp-receiving sockets, and means for supporting said sockets, of means for supporting a globe around said sockets, said globe-supporting means including a pipe extending vertically downward from said socket-supporting means, a member removably secured to said pipe and adapted to engage the globe to support the same around said sockets, a rod vertically guided within said pipe, means for removably securing said rod to said member, and means for limiting the downward movement of said rod.

3. The combination of a pipe, a cross arm secured to said pipe, an insulating block above said cross arm, binding posts carried by said block, a canopy surrounding said pipe, a crowfoot at the lower end of said pipe, a plate carried by said crowfoot and having lamp-receiving openings, sockets upon the upper side of said plate registering with said openings, a pipe extending downward from said plate, globe supporting means telescoping with said rod, and a hood extending over said sockets and globe.

4. The combination of a plate having

- openings, lamp-holders secured upon the upper side of said plate in register with said openings, a reflector below said plate and provided with openings registering with the 5 openings of said first-named plate, a pipe extending downward to a point below said reflector, a rod telescoping into said pipe, a globe having a central opening, and means secured to said globe at said opening for 10 normally coöoperating with said pipe and thereby sustaining said globe, said rod being connected with said last-named means and adapted to sustain said globe when detached from said pipe.
- 15 5. The combination of a pipe, an insulating member at the upper end of said pipe, a binding terminal carried by said insulating member, a cross arm below said insulating member, a plurality of lamp hold-
- ers carried by said pipe, and a reflector below said lamp holders, said reflector having openings for the passage of lamp bases to said lamp holders. 20
6. The combination of a pipe, a reflector carried by said pipe, lamp holders above 25 said reflector, a globe below said reflector, means for normally sustaining said globe immediately below said reflector, and means telescoping with said pipe for sustaining said globe in a lower position at will to 30 afford access to the lamps.
- In witness whereof, I have hereunto subscribed my name in the presence of two witnesses.
